E. H. RYON

WEFT CARRIER MAGAZINE

Filed Oct. 20, 1921

Patented Sept. 11, 1923.

1,467,653

UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-CARRIER MAGAZINE.

Application filed October 20, 1921. Serial No. 509,112.

To all whom it may concern:

Be it known that I, EPPA H. RYON, a citizen of the United States, residing at Waltham, in the county of Middlesex and State 5 of Massachusetts, have invented a new and useful Weft-Carrier Magazine, of which the following is a specification:

This invention relates to a weft carrier magazine for an automatic weft replenishing loom and particularly to means for preventing angular movement or vibration of the weft carriers in the magazine during the loom operation. It is found that weft carriers held in the vertical compartments of 10 a weft carrier magazine of the stationary type receive angular or vibratory motion during the operation of the loom which, if long continued, may weaken the weft ends by chafing between adjacent weft carriers or 15 between the butts of the carriers and parts of the magazine frame. Such angular movement also frequently entangles the weft ends of the different weft carriers and thus interferes seriously with the replacement of an 20 exhausted weft carrier.

It is the object of my invention to provide weft carrier engaging members so designed that they will prevent such angular movement of the weft carriers during the normal 25 operation of the loom but will permit the weft carriers to drop freely as the lower weft carrier in a compartment moves toward transfer position.

The preferred embodiment of my invention 30 contemplates the provision of a weft carrier engaging member for each vertical compartment of the magazine, such members each having a knife-like edge adapted to engage the weft carriers in any angular 35 position thereof and to restrain angular movement of the weft carriers thus engaged.

My invention further relates to arrangements and combinations of parts which will be hereinafter described and more particularly pointed out in the appended claims.

A preferred form of my invention is shown in the drawings, in which—

Fig. 1 is a left hand side elevation of a weft carrier magazine having my improvements embodied therein;

Fig. 2 is a sectional elevation taken along the line 2—2 in Fig. 1;

Fig. 3 is a detail sectional plan view taken along the line 3—3 in Fig. 2; and

Fig. 4 is a detail view of a slight modification.

Referring to the drawings, I have shown portions of a magazine frame 10 adapted to be secured to a loom frame 11 and having a plurality of substantially vertical ribs or guides 12 (Fig. 3) forming compartments or channels for the butts of the bobbins or weft carriers W. These guides are preferably spaced apart so that the compartment is of somewhat greater width than the diameter of a bobbin, and the bobbins dispose themselves in staggered relation as indicated in dotted lines in Fig. 1.

Suitable provision (not shown) is made for guiding and supporting the tips of the bobbins or weft carriers, this part of the magazine being of the usual construction and being shown and described, together with other magazine parts in my prior Patent No. 1,030,748, issued June 25, 1912. These parts include the vertically moving release members or bars 13, locking plungers 14 for said bars, and lifting levers 15 mounted on a cross shaft 16 and adapted to selectively engage and move the bars 13. The shaft 16 is movable both axially and angularly as indicated by the double arrows in Fig. 1.

In the usual operation of the mechanism a bar 13 is raised by a lever 15 to release a weft carrier upon indication of exhaustion of a particular weft carrier. This bar is held in raised position by its plunger 14 until the indicated shuttle returns to transfer position.

For a further description of the actuating mechanism and for a more detailed statement of the operation of these several parts of the magazine, reference is made to my prior patent above mentioned.

My improved weft carrier engaging device in its preferred form comprises a plate 17 for each compartment, slidable in the slot or groove of a rib or projection 18 (Fig. 3) on the inner end wall of the weft carrier compartment. The plates are retained in the grooves by cross pins 19 extending through slots 20 obliquely disposed in the plate 17. Light springs 21 are connected to lugs 22 projecting through openings in the magazine frame and yieldingly force the plates downward and outward against the butts of the weft carriers W. A second lug

or projection 24 on each plate is positioned for engagement by a pin 25 extending laterally from its associated release bar 13.

During the normal operation of the loom, 5 the release bars 13 are in their lower positions and the plates 17 are drawn downward and advanced by the springs 21 so that their knife-like edges engage the butts of the weft carriers with sufficient pressure to practically 10 prevent angular movement or vibration thereof. When, however, a weft carrier is to be released for transfer, its plate will be withdrawn from holding position by upward movement of its bar 13 and will be retained in withdrawn position until downward 15 feed of the weft carriers has occurred.

In Fig. 4 I have shown a slight modification in which the lower slot 25^a in a weft carrier engaging plate 26 is vertically disposed, 20 while the upper slot is inclined as shown in Fig. 2. With this arrangement, the plate 26 just clears the butts of the weft carriers at the lower end of the compartment but is forced outward to engage the weft carriers 25 at the upper end. This arrangement allows greater freedom for the weft carriers about to be transferred while securely engaging and preventing angular movement of the more easily moved weft carriers in the upper 30 part of the compartment.

Having thus described my invention it will be evident that changes and modifications can be made therein by those skilled in the art within the spirit and scope of my 35 invention as set forth in the claims and I do not wish to be otherwise limited to the details herein disclosed but what I claim is:—

1. In a loom, in combination, a stationary magazine having a plurality of vertical weft 40 carrier compartments, devices to prevent angular vibratory movement of the weft carriers in said compartments, and means to render a selected device inoperative upon indication of exhaustion of the weft carrier in a selected shuttle.

2. In a weft carrier magazine, a frame, guides on said frame forming compartments for weft carrier butts, weft carrier engaging members mounted on said frame and yieldingly 50 movable to engage the butts of weft carriers disposed in said compartments, and means to withdraw the member associated with a particular compartment from engagement with the weft carriers therein upon indication of weft exhaustion in an associated shuttle.

3. In a loom, in combination, a stationary

magazine having a plurality of vertical weft carrier compartments, a holding plate mounted in each compartment and yieldingly movable to engage the weft carriers contained therein, and means to withdraw a selected plate from engagement with the weft carriers in the corresponding compartment upon indication of exhaustion of the 65 weft carrier in a selected shuttle.

4. In a loom, in combination, a stationary magazine having a plurality of vertical weft carrier compartments, a holding plate for each compartment having obliquely disposed slots therein, guide pins for said plates fixed in said magazine and extending through said slots, springs for yieldingly moving each plate downward independently, and selective means for raising a particular 70 plate upon indication of exhaustion of the 75 weft carrier in a selected shuttle.

5. In a loom, in combination, a stationary magazine having a plurality of vertical weft carrier compartments, a plurality of plates 80 having knife-like edges movable into engagement with the weft carriers in said compartments, and means to move said plates yieldingly to operative position.

6. In a loom, in combination, a stationary magazine having a plurality of vertical weft carrier compartments, a plurality of plates having knife-like edges movable into engagement with the weft carriers in said compartments, and means to move said plates 85 yieldingly to operative position and selectively and positively to inoperative position.

7. In a loom, in combination, a stationary magazine having a plurality of vertical weft carrier compartments, a plurality of plates 90 having knife-like edges, means to guide the upper portions of said plates downward and inward against the weft carriers, and means to positively withdraw said plates from said 95 weft carriers.

8. In a loom, in combination, a stationary magazine having a plurality of vertical weft carrier compartments, a release bar for each compartment, a weft carrier engaging device in each compartment, means to yieldingly advance each device to weft carrier engaging position, and means to selectively actuate each release bar to withdraw an associated device from weft carrier engagement upon indication of weft exhaustion in 100 a selected shuttle.

In testimony whereof I have hereunto affixed my signature.

EPPA H. RYON.
